UNITED STATES PATENT OFFICE

125,491

DESIGN FOR A CLOCK OR SIMILAR ARTICLE

Kate Lerman, Chicago, Ill.

Application November 14, 1940, Serial No. 96,573

Term of patent 7 years

To whom it may concern:

Be it known that I, Kate Lerman, a citizen of the United States, residing at Chicago, in the county of Cook and State of Illinois, have invented a new, original and ornamental Design for a Clock or Similar Article, of which the following is a specification, reference being made to the accompanying drawings, forming a part thereof, in which

Fig. 1 is a front elevational view of a clock embodying my new design;

Fig. 2 is a plan view of the same;

Fig. 3 is a rear elevational view thereof; and

Fig. 4 is a side elevational view of the same.

I claim:

The ornamental design for a clock or similar article, substantially as shown.

KATE LERMAN.
